UNITED STATES PATENT OFFICE.

CHARLES H. SAMPSON, OF ROCHESTER, NEW YORK, ASSIGNEE TO PEERLESS CHECK PROTECTING COMPANY, OF ROCHESTER, NEW YORK, A CORPORATION OF NEW YORK.

PRINTING-MACHINE.

1,141,270.

Specification of Letters Patent. Patented June 1, 1915.

Application filed October 29, 1913. Serial No. 798,125.

To all whom it may concern:

Be it known that I, CHARLES H. SAMPSON, of Rochester, in the county of Monroe and State of New York, have invented a new and 5 useful Improvement in Printing-Machines, which improvement is fully set forth in the following specification and shown in the accompanying drawings.

The present invention relates to printing 10 machines and an object thereof is to improve the mounting of the platen in that type of machine in which the platen has a serrated face for engagement within grooves on the printing surface for the purpose of bruising 15 or puncturing the paper during the printing operation.

Another object of the invention is to improve that type of printing machine having a rotary type wheel so that all play in the 20 type wheel is eliminated during the printing operation.

A still further object of the invention is to simplify the construction of the feeding mechanism of a printing machine in which 25 the work is given a variable movement to correspond with the matter printed.

A still further object of the invention is to provide a work gage which is so mounted 30 with relation to the work support that the work cannot pass under the same, provision preferably being made to permit the gage to be quickly adjusted and to be held in its adjusted position by a single operating member.

35 To these and other ends the invention consists in certain parts and combinations of parts all of which will be hereinafter described, the novel features being pointed out in the appended claims.

40 In the drawings: Figure 1 is a top plan view of a check writing machine embodying the present improvement, a portion of the indicating means being cut away in order that the work gage, may be seen; Fig. 2 is 45 a section on the line *a—a*, Fig. 1; Fig. 3 is a section on the line *b—b*, Fig. 1; Fig. 4 is a vertical sectional view of the gage operating member; Fig. 5 is a horizontal section on the line *c—c*, Fig. 4; Fig. 6 is a vertical 50 sectional view on the line *d—d*, Fig. 1, the handle or operating member being removed; Fig. 7 is a section on the line *e—e*, Fig. 6; Fig. 8 is a detail view showing the platen adjustment; Fig. 9 is a bottom view with 55 the bottom plate removed to show the in-

terior parts; and Fig. 10 is a section on the line *d—d*, Fig. 1 looking in a direction opposite that of Fig. 6.

Referring more particularly to the drawings, 1 indicates the base frame of the casing which is preferably hollow and is closed by a bottom plate 2. Within this base frame a platen 3 is preferably movably arranged to operate through an opening in the work support 4 which forms a portion of the top of the base frame 1. The platen is preferably arranged on one end of a lever 5 which carries segmental trunnions 8 turning in bearings 9 below the work support 4, this platen carrying lever extending rearwardly in the base 1 and being operated by a mechanism which will be hereinafter described.

The platen 3 is preferably adjustably mounted on the lever 5 in order that its serrations 10 may be made to coöperate 75 properly with the printing surfaces. In this instance, the lever 5 is provided with a transverse groove 11 opening at its opposite ends at the sides of the lever. The platen 3 is a block the opposite sides of which closely 80 hug the side walls of the grooves 11. A screw 12 engages the platen 3 at the center thereof and extends loosely through the bottom wall of the groove 11, its head coöoperating with the under face of the lever to limit the 85 upward movement of the platen but permitting the tilting and also the longitudinal movement of the platen within the groove. The tilting movement may be effected by two screws 13 operating through and having screw 90 threaded engagement with the bottom walls of the groove 11, but merely bearing against the under surface of the platen so that the turning of the screw effects the tilting of the platen about the screw 12 as a fulcrum. 95 The nuts 14 operate on the screws 13 to hold them in their adjusted positions. Longitudinal movement of the platen is effected by two screws 15 which have screw threaded engagement with opposite ends of the platen and lie in the groove 11 and have their heads coöoperating with the side walls of the lever 5 in proximity to the ends of the groove 11. It is apparent that the adjustment of the screws 15 will cause the longitudinal 100 movement of the platen 10 in its groove 11 while the screws do not interfere with the vertical adjustment of the platen.

Arranged above the base frame 1 is an upper casing member 16 which is supported 110

at its rear end by the base member 1 and overhangs the platen 4 providing a way for the passage of the check. Within the overhanging portion of this casing 16, the printing mechanism is arranged to operate.

The printing mechanism preferably embodies the rotary type wheel 17 having lines of type 18 arranged thereon, the types being provided with grooves to receive the serrations of the platen 3, the platen being adjustable as before described in order that the proper matching of the grooves in the type wheel and the serrations of the platen may take place. In this instance, the type wheel turns on the shaft 19 and has a gear wheel 20 rigid therewith in order to be driven or rotated from the oscillatory hollow shaft 21 which carries a beveled gear 22 meshing with a beveled gear 23 which is coaxial with and is secured to a gear 24 that in turn meshes with the gear 25 meshing with the gear 20. The oscillatory hollow shaft 21 extends vertically through the casing 16 in rear of the work support 4, its upper end being provided with a pocket 26 which is slotted at 27 to permit the operating lever or member 28 to be pivoted thereto at 29 and extend into the same in order that its inner end may coöperate with one end of a lever 30, the other end of said lever coöperating with the plunger 31 extending through the hollow shaft and coöperating at its lower end with an adjusting nut 32 which is carried by the platen lever 5, in order that the operating lever 28, which is swung laterally to position the typewheel may also have another movement which shifts the platen to effect the printing operation after the type wheel has been thus positioned. A spring 33, anchored at 34 at its upper end, is connected at 35 to the rear end of the platen carrying lever in order to hold the platen in its lowermost position and at the same time to elevate the plunger so that the operating lever or member 28 will occupy the position shown in Fig. 10.

The position of the printing mechanism may be determined by a pointer or indicator 36 which is secured to and acts as a closure for the pocketed portion 26 of the hollow shaft 21. This pointer operates over a dial 37 provided with matter corresponding to the matter which will be printed by the type wheel. Below this dial a plurality of spaced teeth 38 is arranged in order to permit the operating lever 28 to move downwardly between them to hold such lever against lateral movement while it is being moved vertically for the purpose of effecting the movement of the platen.

With the object in view of preventing any movement of the printing wheel during the printing operation, a locking device is employed comprising preferably a pivoted dog

39 pivoted at 40 within the overhanging extension of the casing and having a nose 41 which is adapted to be wedged between the teeth of the gear 25, the latter having a number of spaces between its teeth corresponding to the number of lines of type on the printing wheel. During the rotation of the printing wheel, this dog lies out of co-operation with the gear wheel 25 but, upon the movement of the plunger 31 a resilient connection such as a spring arm 42 extending from the platen lever 5 and engaging with the dog 39 at 43, shifts the wedge-shaped nose 41 of the dog into engagement with the gear 25, and, as the latter meshes directly with the gear on the type wheel, the type wheel is held against movement while the platen is being moved.

In connection with the machine, a feeding mechanism may be employed which feeds the work, after the printing operation, a distance corresponding to the length of the matter printed by the printing mechanism, it being understood that the printing mechanism necessarily prints different words of various lengths in order to perform its functions as a check writer. This feeding mechanism is preferably in the form of two knurled wheels 44 arranged on a shaft 45 within the base 1 so that they project through openings in the work support in order to engage the work. Upon the shaft 45 a ratchet wheel 46 is rigidly secured. Also arranged upon the shaft to turn loosely thereon, is a swinging arm 47 which carries a spring-pressed pawl 48 for coöperation with the ratchet wheel 46. It is apparent that, when the pawl is moved in one direction by the arm 47, it will ride over the ratchet wheel without affecting the latter but, when moved in the other direction, the ratchet wheel will be compelled to travel with the pawl and the arm 47.

The feeding mechanism may be controlled by the platen operating mechanism and to this end a member 49 extends laterally from the lower end of the plunger 31 and has its outer end guided on the link 50 which is surrounded by a coil spring 51 arranged between said guided portion and a shoulder 52, thus providing a resilient connection between the platen operating mechanism and the feeding mechanism. The link is pivoted at 53 to an arm 54 of a three-armed lever which is pivoted at 55 on the top of the base 1 within the upper casing. The lower arm 56 of this three-armed lever extends downwardly and is connected by a link 57 with the swinging arm 47 so that, when the plunger 31 is moved downwardly, it presses the member 49 downwardly transmitting a movement to the three-armed lever, causing the latter to shift the swinging arm 47 and carry the pawl 48 over the ratchet wheel 46 without shifting said wheel. Upon the re-

turn movement of the three-armed lever due, to the release of the plunger 31, the swinging arm causes the pawl 48 to turn the ratchet wheel and in this way to feed the check for another printing operation.

5 The amount of feed of the feeding device may be determined by a gaging means which is preferably in the form of an irregularly-shaped or shouldered hub 58 preferably integral with the gear wheel 25, the shoulders thereon forming stops for engagement by a laterally-turned end 60 on the third arm 61 of the three-armed lever. It is apparent that, when this three-armed lever is moved 10 on the movement of the plunger 31, its lateral extension 60 will coöperate with one of the shoulders on the hub 58, depending upon which of the shoulders is in its path of movement. It is also apparent that the position 15 of these shoulders must correspond to the lengths of the words on the rotary type wheel in order that the movements of the three-armed lever will correspond with the lengths of the lines on the type-wheel so that the swinging arm 47 and the knurled 20 wheels 44 will have movements to agree with the lengths of the words on the type wheel.

The check may be held firmly to the feed 25 wheels 44 by means of two wheels 76 each co-operating with one of the wheels 44 and carried by a frame 77 which has a finger piece 78 by which the wheels 76 are moved away from the feed wheels 44 against the action of a spring 79.

30 There may be associated with the work support a work gage which determines the position of the check with relation to the printing mechanism. This gage is preferably arranged to one side of the overhanging casing and is preferably in the form of a T-shaped member formed from sheet metal, the cross piece 62 being bent into inverted U-shape and having near its ends depending projections 63 arranged to operate 35 in parallel grooves or depressions 64 formed in the work support 4. The other arm 65 of the T-shaped member may be slotted at 66 and may operate within a way 67 formed in a projection 68 at the rear of the work 40 support.

For the purpose of adjusting the gage and holding it in its adjusted position, there may be provided an operating member 69 preferably in the form of a rotary hand piece 45 turning on a shaft 70 which has screw threaded engagements at its lower end with the projections 68 on the frame of the machine. The upper end of this shaft 70 is provided with a head 71 which serves as an 50 abutment for the coil spring 72 located within a pocket of the hand piece 69 and pressing downwardly on said hand piece to cause the bottom of the latter to bear with yielding 55 pressure against the upper surface of the 55 gage arm 65, thus holding said arm in its

adjusted position. This operating member 69 may be provided with a pocket in its bottom for the reception of a gear or pinion 73, the latter being rigidly secured to the operating member and extending below the latter into the slot 66 of the gage. One wall of this slot 66 is provided with teeth 74 engaged with the teeth of the gear wheel 73 while the other wall is smooth and coöperates with the ends of said teeth. It will thus be seen that 70 the operating member not only serves for moving the gage back and forth, but it holds the gage in its adjusted position. A scale 75 on the work support may be utilized for determining the position of the gage. 80

The operation of the machine may be understood from the foregoing description, but it may be summarized as follows: The check is first placed upon the work support, the gage being adjusted to determine the 85 writing line by means of the hand piece 69 which holds the gage in its adjusted position; and the spring-pressed rollers 76 being raised by depressing the finger-piece 78 to permit the check to pass beneath them. 90 The hand piece 28 is shifted to select the matter which is desired to be written on the check and is depressed after each selection of the desired word. With this depression which occurs after the type wheel 17 has 95 been positioned, the locking dog 39 coöperates with the gear wheel 25 and locks the latter against rotation, after which the platen 3 coöperates with the type wheel. During the adjustment of the type wheel, 100 the gage member or hub 58 is shifted so that the proper shoulder is in position to limit the movement of the three-armed lever of the feeding mechanism prior to the printing after which the lever moves the feed 105 wheels a distance corresponding to the length of the word to be written.

Among the novel features of this invention is the platen adjustment which permits the serrated platen to properly register with the grooves of the printing type on the printing wheel, said adjustment not only permitting the raising and lowering and also the lengthwise movement of the platen, but permitting the plane of its serrated 110 face to be tilted in order that it may be made to correspond exactly with the plane of the printing type. 115

Another feature of the invention is a locking means which prevents all play in the 120 type wheel after the latter has been adjusted.

Still another feature of the invention is the construction of the variable feeding mechanism which employs the fewest number of parts necessary for obtaining the desired operation while maintaining durability and accuracy. 125

A still further feature of the invention is the work gage, the operation of which re- 130

quires but one part to effect the adjustment thereof and the locking of the same in its adjusted position. The gage coöperates with the work support in such a manner 5 that there is no possibility for the work to pass between the gage and the work support.

What I claim as my invention and desire to secure by Letters Patent is:

- 10 1. In a printing machine, the combination with a type wheel having a printing surface provided with grooves, and a platen for coöperation with said printing wheel having serrations for entering the grooves 70 of the printing surface of means for adjusting the platen comprising a support having a way in which the platen may be raised, lowered, and moved longitudinally, a screw having screw-threaded engagement 75 with the under side of the platen and loosely engaging the support, screws having screw threaded engagement with the support and bearing against the bottom of the platen on opposite sides of the first-named screw, and 80 screws having screw-threaded engagement with opposite ends of the platen and loosely engaging the support.
- 15 2. In a printing machine, the combination with a type wheel having a printing 85 surface provided with grooves, of a pivotally mounted lever having a transverse groove, a platen having a serrated face for coöperation with the printing surface and longitudinally movable in the groove of the 90 lever, a screw loosely engaging the lever and having screw-threaded engagement with the bottom of the platen, screws having screw threaded engagement with the lever and bearing against the bottom of the platen 95 on opposite sides of the first-named screw, and screws having screw threaded engagement with opposite ends of the platen and heads bearing against the pivoted lever at the ends of the groove.
- 20 45 3. In a printing machine, the combination with a type wheel having a printing 100 surface provided with grooves, of a pivotally mounted lever having a transverse groove, a platen having a serrated face for coöperation with the printing surface, said platen being mounted in the groove of the 105 lever, means for raising and lowering the platen within said groove, and two screws having screw threaded engagement with 110 opposite ends of the platen and also having heads engaging the lever in proximity to the ends of the groove in order to shift the platen longitudinally within the grooves.
- 25 4. In a printing machine, the combination with a rotary type wheel, of a locking 115 member for holding the type wheel against rotation, a platen lever, a platen carried by the lever and adapted to coöperate with the type wheel, and a connection between the 120 lever and the locking member for moving 125

the latter to locking position and then permitting the lever to continue its movement after the locking member has locked the rotary type wheel.

5. In a printing machine, the combination 70 with a rotary type wheel, of a movable locking dog for holding the type wheel against rotation, a platen for coöperation with the type wheel, and operating mechanism for the platen having a resilient connection with the movable locking dog causing the latter to lock the type wheel before the platen engages the type wheel and then permitting the independent movement of the platen toward the type wheel. 75

6. In a printing machine, the combination with a rotary type wheel, a platen movable toward and from the type wheel to effect the printing operation and gearing connected to the type wheel, of a locking 80 member arranged to coöperate with said 85 gearing, and a member for shifting the platen, said member connected to the locking member to shift the latter into coöperation with the gearing to hold the type wheel 90 against movement when the platen is moyed.

7. In a printing machine, the combination with a rotary type wheel, a platen movable toward and from the type wheel to effect the printing operation, an operating 95 member having one movement to effect the movement of the type wheel and another movement to effect the printing operation, and gearing connecting said operating member and the type wheel to cause the movement of the type wheel when the operating member is moved for such purpose, of a locking dog arranged to interlock with said 100 gearing to hold the type wheel against movement when the operating member is 105 moved to effect the printing operation.

8. In a printing machine, the combination with a rotary type wheel, a platen movable toward and from the type wheel to effect the printing operation and an operating 110 member having two movements, one to shift the type wheel and another to move the platen, of a locking dog for holding the type wheel against movement, and a resilient connection between said locking 115 dog and the operating member, causing said dog to move to locking position before the platen engages the type wheel.

9. In a printing machine, the combination with a rotary type wheel, a platen movable toward and from the type wheel to effect the printing operation, a rotary hollow shaft, gearing connection between said shaft and the type wheel to effect the rotation of the latter, an operating member pivotally mounted on the hollow shaft, a plunger mounted within the hollow shaft and operated by the pivoted operating member, and connection between the platen and the plunger, of a dog for engaging the gear- 130

ing to hold the latter against movement, and resilient connection between the dog and the operating member for causing the dog to enter into engagement with the gear- 5 ing before the platen engages the type wheel.

10. In a printing machine, the combination with a printing mechanism arranged to print words of different lengths, of a work- 10 feeding mechanism comprising a rotary feeding member, a gage member having a plurality of shoulders thereon, and a three- 15 armed lever, one arm having a resilient connection with the printing mechanism, the other arm having a ratchet connection with the feed wheel and the other arm having a rigid laterally extending shoulder for direct engagement with the shoulders on the gage wheel.

20. 11. In a printing machine, the combination with a printing mechanism, and a work support, of a gage for the work on the support, and an operating member for the gage having driving connection with the 25 latter to shift the same and bearing resiliently upon the gage to hold the latter in its adjusted position.

12. In a printing machine, the combination with a printing mechanism and a work 30 support, of a gage for the work on the work support having a rack thereon, and a rotary member resiliently held against the gage and provided with a pinion meshing with the rack to move the gage.

13. In a printing machine, the combination with a printing mechanism and a work support, of a gage for the work on the work support having a slotted portion provided with rack teeth, a rigid shaft extending through said slotted portion, a rotary member 40 turning on the shaft and carrying a pinion meshing with the rack teeth of the slotted portion, and a spring interposed between the shaft and the rotary member to hold the latter with yielding pressure 45 against the gage.

14. In a printing machine, the combination with a printing mechanism and a work support, of a gage for the work on the work support having a slotted portion provided 50 with teeth on one side of the slot, a rigid shaft extending through the slot and having a head at its upper end, a rotary member surrounding the shaft and bearing at its lower end on the slotted portion of the gage, 55 a coil spring interposed between the shoulder on the shaft and the rotary member to cause the lower end of said rotary member to bear yieldingly against the slotted portion of the gage, and a pinion projecting from 60 the lower end of the rotary member into the slotted portion of the gage to coöperate with the teeth on the latter.
